EX

DESIGN FOR A LADY'S COSTUME.

2052

2052

UNITED STATES PATENT OFFICE.

JENNIE SHEILS, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 18,305, dated May 8, 1888.

Application filed April 2, 1888. Serial No. 269,370. Term of patent 3½ years.

To all whom it may concern:

Be it known that I, JENNIE SHEILS, of the city, county, and State of New York, have invented and produced a new and original Design for a Pattern of a Lady's Costume; and I do hereby declare that the engraved prints accompanying this specification convey to any one accustomed to using paper patterns a clear understanding of how a garment made up by to the pattern will appear.

The design shows a basque and a round walking-skirt. The skirt exhibits a full front drapery having a cluster of shirrings below the right hip; a tablier falling in oval outline nearly to the foot of the skirt, revealing the front drapery to the belt at the right side, extending with the effect of a deep lap across the left hip, and displaying draping plaits at the belt; a full center back drapery exhibiting a

deep cluster of shirrings at the top, and full 20 side back draperies displaying draping plaits in the side edges and a fullness at the top. The basque exhibits close-fitting fronts opening above the bust over a full chemisette that displays shirrings at the neck, yoke-pieces 25 on the fronts, a close-fitting back that displays an underfolded double box-plait at the end of its center seam, a standing collar, and coat-sleeves.

What I claim as my invention, and desire to 30 secure by Letters Patent, is—

The design for a lady's costume, as shown in the engraved prints accompanying this specification.

JENNIE SHEILS.
